UNITED STATES PATENT OFFICE.

ROBERT HICKMAN, OF NEW YORK, N. Y.

DESIGN FOR A BELT-PLATE.

SPECIFICATION forming part of Design No. 25,937, dated August 18, 1896.

Application filed June 15, 1896, Serial No. 595,691. Term of patent 7 years.

To all whom it may concern:

Be it known that I, ROBERT HICKMAN, a citizen of the United States, residing at New York, in the county of New York and State of New York, have invented and produced a certain new and original Design for Belts; and I do declare the following to be a full, clear, and exact description of the invention, such as will enable others skilled in the art to which it appertains to make and use the same.

The figure in the drawing is a perspective view of a belt-plate for personal wear, which fully illustrates my design.

The leading feature of my design consists of a belt-plate having the orifices *a b*, parallel sides *c c*, curved ends *e e*, and integral spurs *d d*.

What I claim is—

The design for a belt-plate as herein shown and described.

In testimony whereof I hereunto affix my signature in presence of two witnesses.

ROBERT HICKMAN.
